UNITED STATES PATENT OFFICE.

LLOY E. WHELPLEY, OF BEVERLY, MASSACHUSETTS, ASSIGNOR TO BOSTON MACHINE WORKS COMPANY, OF LYNN, MASSACHUSETTS, A CORPORATION OF MASSACHUSETTS.

INSOLE-TOE-LIP-MOLDING MACHINE.

Application filed August 6, 1921. Serial No. 490,237.

To all whom it may concern:

Be it known that I, LLOY E. WHELPLEY, a citizen of the United States, and resident of Beverly, county of Essex, State of Massachusetts, have invented an Improvement in Insole-Toe-Lip-Molding Machines, of which the following description, in connection with the accompanying drawing, is a specification, like characters on the drawing representing like parts.

This invention relates to machines for molding insoles, and particularly to a machine constructed to mould the toe portion of the in-seam-receiving rib of an insole.

While the machine can be used on any insole having an in-seam-receiving rib, it is especially useful in connection with the type of insole having a body layer of leather or similar material, that is channelled to provide a lip, and a layer of canvas or duck which is adhesively united to said body layer and overlies and reinforces the inner face at least of said lip.

In the manufacture of these insoles, some difficulty is frequently experienced in pressing the duck or canvas layer firmly against the lip at the toe portion of the shoe, especially where the insole has a very pointed toe.

My invention provides a machine adapted to operate on the toe of an insole and arranged to firmly press the canvas layer against the inner face of the upturned lip at the toe portion, and also arranged to mould or shape this lip at the toe portion, so that it will have the correct contour.

In order to give an understanding of my invention, I have illustrated in the drawings a selected embodiment thereof, which will now be described, after which the novel features will be pointed out in the appended claims.

Fig. 1 of the drawings is a side view of a machine embodying my invention.

Fig. 2 is a plan view of the molding elements, showing the manner in which they operate on the insole.

Fig. 3 is a section on the line 3—3, Fig. 2.

Fig. 4 is a perspective view of the toe portion of an insole, showing the manner in which one of the mould members operates thereon.

The machine herein illustrated is provided

with a base or bed 1, on which the insole 2 is supported, and it is also provided with two mould members adapted to engage the outside and inside of the toe portion of the in-seam-receiving rib, and press or mould said portion into the desired shape.

The insole 2 is of the familiar type having the upturned in-seam-receiving rib 3, and the feather edge 4 exterior to the rib. The insole shown in Fig. 4 is of the type having a reinforcing layer 5 of canvas or duck which is cemented to the body portion of the insole, and which overlies the inner face of the in-seam-receiving rib.

As stated above, difficulty is frequently experienced in properly pressing together the fabric layer and the upturned lip of the insole body at the toe portion of the insole, especially where the insole has a very pointed toe, as shown in the drawings.

The mould members which are designed to accomplish this are herein indicated at 6 and 7 respectively. The mould member 6 is detachably secured to the bed 1 by means of suitable clamping screws 8, and it is provided with a reentrant portion 9 of a shape to fit the outside face of the toe portion of the in-seam-receiving rib 3. Said mould is also provided on its under face with a recess 10 of the proper dimensions to receive the feather edge 4 of the insole, so that when the insole is placed on the bed, the feather edge at the toe portion may be inserted into the recess 10, and the rib 3 fitted into the reentrant portion 9.

The mould member 7 is of the proper shape to fit the inner face of the rib 3 at the toe portion, and the machine is so constructed that when it is operated, the mould member 7 will be brought against the face of the insole, as shown in Fig. 4, and will then be moved forwardly into the angle 11 formed by the toe portion of the in-seam-receiving rib, thereby to mould said toe portion between itself and the reentrant portion 9 of the member 6. The mould member 7 is at the same time pressed against the insole, so that the fabric layer 5 will be firmly pressed against the body of the insole at the toe portion.

One of the mould members is preferably heated so that the molding operation will be accomplished by both heat and pressure,

and I have herein shown the mould member 7 as heated.

Any suitable means may be employed for actuating the mould member 7. It is herein shown as provided with ears 12, which are pivotally connected to a member 13, as shown at 14. This member 13 is provided with a slot 15, which is received in the forked end of an upright 16, that rises from the bed 1, 10 said upright having a pin 17 extending through the slot.

The link 18 is pivotally connected to the member 13 at 19, and also pivotally connected at 20 to an arm 21, which in turn is pivoted 15 to the bed at 22. This arm 21 is connected by a link 23 to a treadle 24. The arm 21 is acted upon by a return spring 25, one end of which is connected to the treadle 23 and the other end of which is connected to the 20 bench 30 on which the machine is supported, as shown at 26. When the treadle 24 is free, the spring 25 will raise the arm 21 into the dotted line position, and said arm acting through the link 18, will raise the 25 member 13 and mould the member 7 into the dotted line position. When in this position, said mould member is elevated above the bed, so that the latter is free to receive the insole to be moulded. After an insole 30 has been placed on the bed in the position shown in Figs. 1 and 2, the pressure is applied to the treadle, thereby moving it into the full line position Fig. 1. This operates through the link 23, arm 21 and link 18, to 35 bring the mould member 7 against the insole with a downward pressure, and also operates to move the mould member 7 into the re-entrant portion 9 of the mould member 6, with the result that the toe portion of the 40 in-seam-receiving rib 3 will be moulded into the desired shape between said mould members. To produce a sufficient downward pressure of the mould member 7 against the insole, I provide the member 13 with a roll 45 28, adapted to pass under a flange or arm 29 extending from the upright 16 as said member 13 is moved into the full line position. This arm 29 and roll 28 cooperate with the link 18 to give the mould member 50 7 not only a forward movement into the reentrant portion 9, but also a downward movement against the insole.

The mould member 7 is heated, and this is accomplished by providing the member 13 55 with an electrical heating unit indicated at 27, said heating unit operating to heat the member 13, and also to heat sufficiently the member 7.

The operation of molding an insole involves simply the placing of the insole into 60 the machine, and then the depressing of the treadle 24.

The heating of the mould member 7 is 65 advantageous because the heat softens the cementitious substance by which the duck

layer is attached to the insole thus permitting the duck to be crowded firmly into the corner of the rib at the toe portion.

In the manufacture of shoes it is highly advantageous to have the toe portion of 70 the rib 3 correctly formed because when the rib is properly shaped at the toe portion it is possible to last the toe of the shoe more evenly and also to stitch the shoe better than if the rib is imperfectly formed. 75

I will preferably make the arm 29 slightly resilient so that it will give sufficiently to accommodate insoles of different thickness.

I claim:

1. In a machine of the class described, the 80 combination with a stationarily-mounted mould member having a shape to fit the exterior face of the toe portion of an in-seam-receiving rib on an insole, of a second mould member shaped to fit the inside face of said 85 rib, a swinging member to which said second mould member is pivotally connected, means to give the swinging member a swinging movement to cause the second mould member to move toward the first in the general direction of the length of the sole being 90 operated on, and means to heat said swinging member and thereby to heat the second mould member.

2. In a machine of the class described, the 95 combination with a stationarily-mounted mould member having a shape to fit the exterior face of the toe portion of an in-seam-receiving rib on an insole, of a second mould member shaped to fit the inside face of said 100 rib, a swinging member to which said second mould member is pivotally connected, means to give the swinging member a swinging movement to cause the second mould member to move toward the first in the general direction of the length of the sole being 105 operated on, means to heat said swinging member and thereby to heat the second mould member, and means to cause the second mould member to apply pressure to the body of the insole transversely thereof.

3. In a machine of the class described, the combination with a stationarily-mounted mould member having a shape to fit the exterior face of the toe portion of an in-seam- 115 receiving rib on an insole, of a second mould member shaped to fit the inside face of said rib, means to move the latter mould member toward the former member, thereby to mould said rib between them, and means to cause said latter member to apply pressure to the body of the insole transversely thereof.

4. In a machine of the class described, the 125 combination with a stationarily-mounted mould member constructed to fit the exterior face of the toe portion of the in-seam-receiving rib on an insole, of a swinging member, a second mould member pivotally mounted thereon and shaped to fit the inner face of 130

said rib, means to give said member a swinging movement toward the stationary mould member in a direction substantially parallel to the insole being operated on, a stationary 5 cam member, and a roll carried by said swinging member and engaging the cam member thereby to cause the movable mould member to apply pressure to the insole transversely thereof during the molding operation.

10 5. In a machine of the class described, the combination with a stationarily-mounted mould member constructed to fit the exterior face of the toe portion of the in-seam-receiving 15 rib on an insole, of a swinging member, a second mould member pivotally mounted thereon and shaped to fit the inner face of said rib, means to give said member a swinging movement to cause the mould members 20 to move relatively to each other, a stationary cam member, and a roll carried by said swinging member and engaging the cam member thereby to cause the movable mould member to apply pressure to the insole during 25 the molding operation, and means for ap-

plying heat to said swinging member, thereby to heat the movable mould member.

6. In a machine of the class described, the combination with a bed constituting a work support, of a mould member secured 30 thereto and having a shape to fit the exterior face of an in-seam-receiving rib on an insole, and also having a portion to overlie the further edge of the insole, of a post rising from said bed, a member having a 35 sliding pivotal connection with the post, a second mould member pivotally mounted on said member and having a shape to fit the interior face of said rib, means to give said member a swinging movement to bring the 40 mould members relatively into molding position, a projection extending from said post, and a roll carried by the swinging member and engaging said projection thereby to produce downward pressure of the 45 movable mould member against the insole.

In testimony whereof, I have signed my name to this specification,

LLOY E. WHELPLEY.
